JOHN TITUS, OF OYSTER BAY, AND WILLIAM TITUS, OF OLD WESTBURY, NEW YORK.

VENTILATING APPARATUS.

SPECIFICATION forming part of Letters Patent No. 699,352, dated May 6, 1902.

Application filed August 17, 1901. Serial No. 72,436. (No model.)

To all whom it may concern:

Be it known that we, JOHN TITUS, a resident of Oyster Bay, and WILLIAM TITUS, a resident of Old Westbury, in the town of North Hempstead, in the county of Nassau and State of New York, citizens of the United States, have invented certain new and useful Improvements in Ventilating Apparatus; and we do hereby declare that the following is a full, clear, and exact description of the same, reference being had to the accompanying drawings, making a part of this specification, in which—

Figure 1 is a partial vertical sectional view of a ventilating apparatus made according to our invention. Fig. 2 is a horizontal sectional view thereof, taken in the line $x'x$ of Fig. 1. Figs. 3 and 4 are detail views of devices included in the apparatus.

20 This invention relates to that class of ventilating apparatuses in which two volumes or streams of air of different temperatures are mingled prior to their access to the room or place to be ventilated.

25 The object of said invention is to provide simple and effective means for automatically regulating and controlling the temperature, volume, and pressure of the commingled air as the same is supplied to said room or place.

30 To this end the invention comprises certain new and useful combinations of parts hereinafter fully described and specified in the claims appended hereto.

A is a cooling-chamber or cooler, which may be of any suitable construction—as, for example, and as shown on the drawings, an ice-box with a horizontal diaphragm a , by means of which a circuitous passage is given to the air as it passes through to more thoroughly 35 refrigerate the same. From the cooling-chamber extends upward a vertical cold-air shaft B, and placed in suitable relation with the cooling-chamber is an air-forcing apparatus, preferably, and as shown in the drawings, a

40 rotary fan-blower C, which may be driven by a pulley b , and whereof the inlet from the atmosphere or from any desired source of air-supply is shown at c in Fig. 1. This air-forcing apparatus or blower C has two outlets e and d , which extend from the throat of the

blower, as shown in Fig. 1. Of these outlets d communicates with the cooler A, while e communicates with a secondary vertical air shaft or pipe D, which is parallel with the cold-air shaft B, so that in the operation of 55 the blower C air is simultaneously forced into the secondary air-shaft D direct from the blower and into the cooler A and thence into the cold-air shaft B. In the throat e of the blower is provided a swinging valve E, which 60 acts in conjunction with vents a' b' at opposite sides of said throat, as shown in Fig. 1. This valve is so arranged that by adjusting it in one direction or the other the supply of air to the one shaft or the other may be increased or diminished at will, the air-supply to the one shaft being diminished as that of the other is increased, and conversely, while by bringing the valve against one or the other of its vents the supply of air to one or the other, as the case may be, of said shafts may be entirely cut off. The required adjustment may be given to this valve by means of an arm a^4 , attached to an outer end of its pivot b^4 and held by a pin c^4 , which passes through 65 a hole in the arm into any one of several corresponding holes in a fixed section d^4 , as shown.

Located between the two air-shafts B and D is a mixing-chamber E, which at one end 8c communicates with the cold-air shaft B and at the other with the air-shaft D. The end of this mixing-chamber which communicates with the shaft B has a register f , preferably of the semirotative kind, for controlling the 85 inflow of air from said shaft to said chamber. In like manner and for like purpose that end of the chamber which communicates with the secondary shaft D is provided with a register g . Each of these registers has a radial arm h , and these arms of the two registers are connected by a rod i , so that an impulse or movement given to the one register will be transmitted to the other. The registers are so provided that when one of them opens 90 or enlarges its passages to increase the volume of air passed therethrough the other will in the same ratio be closed more or less, and vice versa. The rod i is connected in any suitable way—as, for example, by a link j — 100

with the movable part of a suitable thermostat *F*, so that changes of temperature acting upon the registers *f* and *g* the relative volumes of air passed into the mixing-chamber 5 from the two air-shafts are automatically controlled. The mixing-chamber has an outlet into the room or place to be ventilated. This outlet is shown at *k* and is provided with a register *m*, by which the outflow of air therefrom may be controlled. The thermostat just hereinbefore mentioned should of course be suitably placed in the room or place to be ventilated. To the register *m* of the outlet *k* of the air-mixing chamber *E* is provided a 15 projecting tube or nozzle *n*, to which in any suitable manner is attached a flexible tube *G*. The free end of this flexible tube being open, air may be conducted at will to any part of the room or place to be ventilated—as, for 20 example, into any desired relation with a couch, bed, chair, or the like, as may be desired.

Upon the chamber *E* and with its lower end communicating with said chamber is a cylinder *H*, in which is a longitudinally-movable plunger *I*, the upper projecting end of which bears against the under side of a loaded lever *J*. This lever is connected by a link *r* with a crank-arm *s* on the register *m* of the 25 outlet *k* of the chamber. When the pressure within the chamber exceeds a desired or fore-determined limit, the plunger *I* is lifted, thereby actuating the lever *J* to operate said register to more or less close the same, thereby 30 regulating the volume of the mixed air from the chamber to the room or place to be ventilated and controlling the pressure under which it is so admitted to an extent proportioned to the degree to which the air is throttled in its passage through said register. Any 35 desired number of mixing-chambers and their herein-described adjuncts may be employed in connection with the two air-shafts, according to the number of stories of the structure 40 to be ventilated. The two volumes of air, that from the air-shaft *D* being of the higher temperature—as, for example, the normal temperature for the time being of the outer atmosphere—while that from the cold-air 45 shaft is refrigerated or of lower temperature, meet and commingle in the mixing-chamber, and thus reach a temperature common to both before issuing from said chamber to the room or place to be ventilated.

50 55 What we claim as our invention is—

1. The combination with an air-cooler, a cold-air shaft extended upward from said cooler, a secondary air-shaft parallel with the cold-air shaft, and an air-forcing apparatus 55 at the lower ends of the air-shafts for forcing air simultaneously to said shafts, of a mixing-chamber between the two air-shafts communicating therewith, and having an outlet to the room or place to be ventilated, registers at the inlets from said air-shafts to said mixing-chamber, and mechanism for simul-

taneously operating the registers to regulate the relative volumes of air from the two shafts into the chamber, substantially as described.

2. The combination with an air-cooler, a 70 cold-air shaft extended upward from said cooler, a secondary air-shaft parallel with the cold-air shaft, and an air-forcing apparatus at the lower ends of the air-shafts for forcing air simultaneously to said shafts, of a mixing-chamber between the two shafts and having an outlet to the room or place to be ventilated, registers at the inlets from said shafts to said mixing-chamber, a thermostat and devices for connecting the thermostat with 80 said registers to automatically actuate said registers by the temperature of the room or place to be ventilated, substantially as described.

3. The combination with an air-cooler, a 85 cold-air shaft extended upward from said cooler, a secondary air-shaft parallel with the cold-air shaft, an air-forcing apparatus at the lower ends of the shafts, for simultaneously forcing air thereto, and a valve at the throat 90 of said apparatus for regulating the relative volumes of air supplied to the two shafts, of an air-mixing chamber between the two shafts and communicating therewith, registers at the inlets from said air-shafts to said chamber, and mechanism for simultaneously operating the registers to regulate the relative volumes of air from the two shafts into the 95 chamber, substantially as described.

4. The combination with an air-cooler, a 100 cold-air shaft extended upward from said cooler, a secondary air-shaft parallel with the cold-air shaft, an air-forcing apparatus at the lower ends of said shaft for simultaneously forcing air thereto and a valve at the throat 105 of the air-forcing apparatus for regulating the relative volumes of air supplied to the two shafts, of an air-mixing chamber between the two shafts and communicating therewith, registers at the inlets from the shafts to the 110 chamber, a thermostat, and devices for connecting the thermostat with the registers to automatically actuate the registers by the temperature of the room or place to be ventilated, substantially as described.

5. The combination with an air-cooler, a cold-air shaft extended upward from said cooler, a secondary air-shaft parallel with the cold-air shaft, and an air-forcing apparatus 120 at the lower ends of two air-shafts for forcing air simultaneously to said shafts, a mixing-chamber between the two shafts and having an outlet to the room or place to be ventilated, registers at the inlets from the shafts to the chamber, and a register at the outlet 125 of the chamber, into the room or place to be ventilated, of a device actuated by pressure of the air within the chamber and mechanism for transmitting motion from said device to the register at the outlet of the chamber, 130 substantially as described.

6. The combination with an air-cooler, a

5 cold-air shaft extended upward from said cooler, a secondary air-shaft parallel with the cold-air shaft, and an air-forcing apparatus at the lower ends of said shafts for forcing air simultaneously thereto, of a mixing-chamber between the two shafts, and having an outlet to the room or place to be ventilated, registers at the inlets from the shafts to the chamber, of a register at the outlet from the chamber to the room or place to be ventilated, an arm provided to said register, a cylinder, the lower end of which communicates with the said chamber, a plunger in said cylinder with its upper end projected from the top thereof, 15 a loaded lever actuated from the plunger, and means for connecting said lever with the register at the outlet of the chamber whereby said register is actuated from the varying pressure within the chamber to regulate the outflow of air from the chamber to the room or place to be ventilated, substantially as described.

20 7. The combination with an air-cooler, a cold-air shaft extending upward from said cooler, a secondary air-shaft parallel with the cold-air shaft, and an air-forcing apparatus at the lower ends of the two shafts, of a mixing-chamber between the said shafts and having an outlet to the room or place to be ventilated, a flexible air-conducting pipe connected to said outlet, registers at the inlets from the two air-shafts to the chamber and mechanism for actuating said registers to regulate the admission of air from the shafts to the chamber, substantially as described.

25 8. The combination with an air-cooler, a cold-air shaft extended upward from said cooler, a secondary air-shaft parallel with the cold-air shaft, and an air-forcing apparatus at the lower ends of said shafts, of a mixing-chamber between said shafts and having an outlet to the room or place to be ventilated, a flexible air-conducting pipe connected to said outlet, a register at said outlet, a pressure-regulator connected with said register, registers at the inlets from the two shafts to the mixing-chamber, and mechanism for simultaneously operating the said registers to

regulate the relative volumes of air passed from the shafts to the chamber, substantially as described.

9. The combination with an air-cooler, a cold-air shaft extended upward from said cooler, a secondary air-shaft parallel with the cold-air shaft, an air-forcing apparatus at the lower ends of the shafts, and a valve in the throat of said apparatus to regulate the relative volumes of air passed therefrom to the two air-shafts, of a mixing-chamber between said shafts and having an outlet to the room or place to be ventilated, a flexible air-conducting tube connected to said outlet, a register at said outlet, a pressure-regulator connected to said register, registers at the inlets of the two shafts to the mixing-chamber, a thermostat, and mechanism for actuating the said registers from changes in the temperature of the room or place to be ventilated, substantially as described.

10. The combination with an air-cooler, a cold-air shaft extended upward from said cooler, a secondary shaft parallel with the cold-air shaft, an air-forcing apparatus at the lower ends of said shafts, and an adjustable valve in the outlet-throat of the air-forcing apparatus to regulate the relative volumes of air passed therefrom to the two shafts, of a mixing-chamber between the two shafts and having an outlet to the room or place to be ventilated, a register at said outlet, a pressure-regulator connected to said register, a flexible air-conducting tube connected to said outlet, registers at the inlets from the two air-shafts to the air-mixing chamber, a thermostat, and mechanism connecting the thermostat with said registers to simultaneously actuate the same from the varying temperature of the room or place to be ventilated, substantially as hereinbefore described and set forth.
